UNITED STATES PATENT OFFICE.

MALVA NADOLLECK, OF NEW YORK, N. Y.

DESIGN FOR A WREATH.

Application filed August 21, 1925. Serial No. 14,546. Term of patent 3½ years.

To all whom it may concern:

Be it known that I, MALVA NADOLLECK, a citizen of the United States, residing at 126 East 10th Street, New York city, in the county of New York and State of New York, having invented a new, original, and ornamental Design for Wreath, of which the following is a specification, reference being had to the accompanying drawings, forming part thereof.

The figure is a plan view of a wreath showing the design.

I claim:

The ornamental design for a wreath, as shown.

MALVA NADOLLECK.
